UNITED STATES PATENT OFFICE.

FRED A. TRACEY, OF PORTLAND, OREGON.

METHOD OF CONSTRUCTING AND SUPPORTING FORMS FOR CONCRETE WORK.

Application filed February 10, 1928. Serial No. 253,405.

My present invention has reference to a method of constructing and supporting forms for concrete work whereby any desired form that comprises form units designed to be 5 bolted together may be obtained, the said units being readily unbolted and removed without injury to the units, so that the form can be practically continuously used.

Among the objects of the invention I seek 10 to obtain a form construction that can be easily and quickly erected; one in which time is saved in stripping or taking down the form, one wherein all of the materials comprising the same are re-usable, wherein the units constituting the form can be rigidly connected 15 and, therefore, produce a stronger construction than is usual; one in which perfect alinement of all the form units will be readily obtained, changes in the form after erection 20 made without confusion or litter, and further wherein the form units may be assembled or disassociated without the employment of skilled labor.

To the attainment of the above desired results, the improvement also resides in certain other novel features of construction, combination and operative association of parts, one satisfactory embodiment of which is disclosed by the accompanying drawings.

30 In the drawings:

Figure 1 is a top plan view of the form for concrete work in accordance with this invention.

Figure 2 is a sectional view approximately 35 on the line 2—2 of Figure 1.

Figure 3 is a perspective view of one of the main form units.

Figure 4 is a similar view of one of the inner corner form units.

Figure 5 is a perspective view of one of the 40 outer corner posts for the form.

Figure 6 is a similar view of the beams which connect the form units.

Figure 7 is a sectional view approximately 45 on the line 7—7 of Figure 1.

Figure 8 is a sectional view approximately on the line 8—8 of Figure 1.

Figure 9 is a sectional view approximately 50 on the line 9—9 of Figure 2.

Figures 10 and 11 illustrate two of a multiplicity of spacer strips or elements which may be employed for widening the form.

Figure 12 is a perspective view of the corner posts employed when the form is constructed at other than a right angle.

One of what I will term the main form units is illustrated in detail in Figure 3 of the drawings. These units are employed upon both the inner and outer faces of the form and as disclosed by the drawings, each of said units 60 is of the same height and width. These units in the drawings are broadly indicated by the numeral 1. Each of the units comprises a frame which, in the showing of the drawings is substantially rectangular. The 65 units 1, and the remainder of the improvement may be constructed of any desired material, wood, however, being preferred. Each unit 1 is of a size to permit of the convenient handling thereof. For distinction the vertical or end posts of the frame of each of the units 1 is indicated by the numeral 2 and the top and bottom beams connecting the posts 2, by the numeral 3. There are intermediate vertical beams 4 whose ends are secured to 70 the inner faces of the beams 3 and transverse plates 5 connecting the intermediate plates or beams 4 and the side beams or posts 2. In this manner it will be seen that the frames constituting the units 1 present a strong and 75 rigid construction. The frames of each of the units have a facing 6 of shiplap or other suitable material, which facing in turn, is faced with a metal sheet 7. These facings, 80 it will be noted also materially reinforce the frame, and the metal facings will effect in obtaining more perfect results than is possible with ordinary wood forms for concrete work. However, for rough work the metal facing 85 may be dispensed with. All of the outer edges of the forms 1, that is, the elements 2 and 3 are bored with standard sized bolt holes 9, and these holes are bored on exactly 6" centers and 6" from each corner of the units, 90 and also at an equal distance from the facing 95 of the units. The holes are bored at this distance to allow for bolt heads and large sized washers and nuts which are screwed on the bolts being received inside of the frames. The bolt holes arranged 6" apart may be referred to as the standard boring and the spacing of all bolt holes on all of the form units 100 are uniform, thus providing complete interchangeability and exact alinement at the joints. Ordinary standard units of certain 105 size may be used with shorter or narrower units only to fill up the required dimensions.

The form units 1 are arranged one over the other and are connected by bolts 9 and nuts which pass through the openings 8 in 110

the upper and lower beams 3 of the said units, (see Figure 7). The side or end beams 2 of the adjacent units are not in direct contact with each other, the same being held from such contact by the arrangement there-between of posts 10 which I shall refer to as form supports. These posts 10 are of rectangular formation and are made in convenient lengths which are multiples of 6" and are provided with transverse bolt holes 11 which are arranged 6" apart. The form supporting posts are arranged one over the other and the bolt holes 11 nearest the ends of the said posts are disposed 3" from said ends. When it is found necessary to cut these posts the bolt openings from the said ends must be always arranged 3" from the said ends so that the bolt openings 11 will align with the bolt openings 8 in the form units 1, so that bolts 12 engaged by suitable nuts pass through the said bolt openings 8 in the units 1 and the bolt openings 11 in the form supporting posts 10. The heads of the bolts 9 and 12 contact with suitable washers and the nuts 13 which are screwed on these bolts also contact with washers. The form supporting posts 10 are provided with spaced series of openings 14 arranged right angularly with respect to the bolt openings 11 and these openings 14 are designed for the reception of spacer and tie wires 15 which properly space the inner and outer mold units.

The joints between the posts 10 are broken with respect to the joint or meeting ends of the superimposed mold units 1 so as not to weaken the construction. When the mold is to be widened, spacer elements, such as posts or strips 15 and 16, disclosed particularly by Figures 10 and 11 are disposed between the form supporting posts 10 and the sides of the units 1. These strips 15 and 16 are also preferably of wood and are bored transversely to provide bolt openings 17 which are spaced 6" apart. The only waste in the form construction will result in the cutting of the spacer strips or posts and the cutting in the form supporting posts 10.

The inner corner form units each comprises a right-angular frame which is best illustrated by Figure 4 of the drawings. These corner form units are indicated by the numeral 18, the outer posts or uprights therefor being indicated by the numeral 19, the inner posts or uprights by the numeral 20 and the upper and lower strips or beams which connect the posts 19 and 20 by the numerals 21. The top and bottom members 21 are bored to provide bolt openings 22 which are spaced 6" away from each other, and 6" away from the corners, the posts 20 having similarly spaced bolt openings 23. The posts 19 and 20 are connected by transverse brace strips 24, and the inner corners 65 of the posts 20 are connected by angle brace

members 25. The outer surface of the frame of the inner form units has a facing 26 similar to the facing on the units 1, is in turn covered by a metal facing 27 similar to the metal facing 7. Of course, the inner corner units are arranged one over the other and are bolted together in a manner similar to the units 1, and the posts 20 of the inner corner units are bolted to the posts or uprights 2 of the units 1, adjacent thereto or rather to the form support 10 and if necessary to the spacer strips 15 and 16 as well as to the posts 10, when it is found necessary to employ the said spacing strips.

The end units for the outer wall of the form, that is the units adjacent to the outer corners of the form are similar to the units 1, but, of course, are narrower. These units also are, of course, of a greater length than the sides of the inner corner units 18 and the ends of these units indicated for distinction by the numerals 28, have bolted thereto corner posts 29 illustrated in Figure 5 of the drawings. The outer posts of the units 28 have the bolt openings therethrough spaced 6" apart, but the series of openings in the said posts are staggered with respect to each other so that one of such series of bolt openings will align with the bolt openings 30 that pass transversely through the posts 29 and the other series will register with bolt openings 31 that are arranged right angularly but out of line with the bolt openings 30. By this arrangement it will be seen that the bolts that connect the corner posts to the outer corner units of the form are disposed a slight but suitable distance away from each other.

It is, of course, necessary to brace or shore the form units so that the same will not bulge when concrete is poured into the form. In the drawings I have illustrated the shores or braces applied to only the inner form units. On certain of the posts or uprights of the form units I arrange brackets of a particular and peculiar construction. Each of these brackets comprises a substantially rectangular body portion made up each of a lower plate 32 bolted, in the showing of the drawings, to the posts of the units 1 and an outer plate 33 bolted to the outer end of the plate 32, the connecting bolt between the plates 32 and 33 also securing thereto an angle brace plate 34 which is bolted to the said upright of the unit 1. The upper end of the plate 33 is connected by a removable pivot 35 to the upper plate 36 which is bolted to the upright or post of the unit 1. By removing the pivot it will be noted that the plates 33 and 36 will be swung away from each other which permits of a beam 37 being received in the bracket and supported upon the plate 32. After the beams 37 are thus arranged the plates 33 and 36 are swung toward each other and the pivot inserted through the pivot openings therefor.

Also after this is effected wedge elements 38 are inserted between the plates 33 and 36 for frictionally contacting with the beam 37.

Received through the beams 37 there are 5 eye bolts 38 which, of course, are engaged by nuts. The headed or eye ends of the bolts 38 are disposed upon the inner or confronting faces of the beams 37, and these ends or heads have pivotally secured thereon the bifurcated 10 end or head portions 39 of screws 40. Each screw 40 is threaded through an opening in the outer end of a metal sleeve 41 that surrounds and is secured to a shoring beam 42. The ends of the shoring beams 42 that receive 15 the screws 40 therein are, of course, provided with sockets 43. Threaded on the screws and contacting with the outer ends of the sockets 43 there are adjusting nuts 44. The shoring beams 42 are each provided with equidistantly spaced bolt openings 45, and the respective pairs of cooperating shoring beams are designed to have their ends arranged one over the other and through the alining openings in these lapping ends there are passed bolts 20 46 which are, of course, engaged by nuts.

By adjusting the nuts 44 on the screws 40 the adjustably connected shoring beams will be moved longitudinally with respect to the units of the form and effectively sustain such 25 units in proper spaced relation to each other.

When the sides of the form are disposed at other than a right angle, corner posts 47, such as illustrated by Figure 12 of the drawings are employed, it being noted that the face 48 30 of said beam 47 is beveled and cut at an angle.

It is believed the simplicity and advantages of my construction will be fully understood and appreciated by those skilled in the art to which such invention relates, when the foregoing description has been carefully read in connection with the accompanying drawings, but obviously I do not wish to be restricted to the precise details of construction herein set forth, and, therefore, hold myself entitled 40 to make such changes therefrom as fairly fall within the scope of what I claim. It is to be further understood that while I have mentioned the bolt openings being arranged six inches from center to center, the said openings 45 may be otherwise spaced, it being only necessary that the bolt openings be arranged equidistantly from each other throughout the form construction.

Having described the invention, I claim:

55 1. A form for concrete work, comprising inner and outer spaced units, each of which including a frame, of the same height and

width, and each of said frames having a facing, the outer elements of each frame having equidistantly spaced openings therethrough for the reception of bolts therethrough when the units are arranged side by side and one over the other, vertical form supporting posts through which the side bolts pass and spacer wires passing through transverse openings in the inner and outer supporting posts and spacer strips between the form supporting posts and form units through which the bolts also pass, breakable brackets on certain of the inner form units, eye bolts carried thereby, screws pivoted to the eye bolts, adjustably connected shore beams having sockets in the ends thereof for the screws and nuts threaded on the screws for contacting with the ends of the shore 75 beams.

2. A form for concrete structures, comprising inner and outer units, all of which include frames of the same size and dimensions except the corner units, all of said frames having facings and the ends and edges thereof of being provided with equidistantly spaced bolt receiving openings, the inner corner frames being of triangular formation and braced, said units designed to be arranged edge to edge and in superimposed relation and to have bolts passing through the registering openings therein, form supporting posts having equidistantly spaced bolt openings therethrough that are arranged between 80 the confronting edges of the units and receiving the bolts therethrough, spacer strips between the form supporting posts and the frame units having equidistantly spaced openings for the reception of bolts, wire members passing transversely through the form supporting posts, corner posts for the corners of the outer frame units having equidistantly spaced bolt openings for the reception of the bolts therethrough, collapsible brackets removably and adjustably secured to the inner frame units, a beam supported in the brackets, wedge elements securing the beam in the brackets, shorings between the brackets, each comprising adjustably connected beams having sockets through the ends thereof, a casing surrounding said ends, swingably supported screws on the beams received through said casings and into said sockets and nuts threaded on said screws for 85 contacting the casings.

In testimony whereof I affix my signature.

FRED A. TRACEY.
